UNITED STATES PATENT OFFICE.

HENRY WARDEN, OF PHILADELPHIA, PENNSYLVANIA.

SECTIONAL BOILER.

SPECIFICATION forming part of Letters Patent No. 364,982, dated June 14, 1887.

Application filed February 10, 1887. Serial No. 237,098. (No model.)

To all whom it may concern:

Be it known that I, HENRY WARDEN, of Philadelphia, State of Pennsylvania, have invented a new and useful Improvement in Sectional Boilers, of which the following is a true and exact description, due reference being had to the accompanying drawings, which form a part hereof.

My invention relates to that kind of steam-generators known as "sectional boilers," and has for its object to provide a steam-generator which will combine the advantages of the best types of such boilers now in use with improved furnace-flue arrangements and devices for drying and superheating the steam generated in the water tubes and heaters. A further object of my invention is to so construct my boilers that they may be transported in comparatively small and light sections, and at the same time be readily put up. This I accomplish in the manner hereinafter described, and illustrated in the accompanying drawings, in which—

Figure 1 is a side sectional view of my improved boiler as erected and ready for use, and Fig. 2 is a front elevation of the boiler.

A is the ordinary masonry inclosing the boiler; *c c c*, water-tubes set at an incline and secured in headers C.

I I I are pipes connecting the front headers with the steam and water receptacle H.

J represents similar pipes connecting the back headers with the receptacle H. H, which here corresponds to the ordinary steam and water drum of the Babcock and Wilcox boiler, which is the general trade-name for boilers of this class, is made up of the well-known Harrison elements of cast-iron, said elements being cast of substantially spherical form and securely clamped together to form a generator boiler or receptacle consisting of a mass of hollow spheres connected by collars, ground joints, or short tubes.

N N are pipes leading from the upper end row of spherical elements to the steam conduit O P.

D is the furnace grate; E, a deflecting-wall extending upward from the back of the grate to or nearly to the top of the tubes *c*; F, a deflecting wall or bridge extending down to or about the bottom of the tubes *c*.

G is a wall or partition separating the fur-

nace-flues which surround the lower parts of the boiler from the upper flue, L.

K is an opening in the partition G.

L is a flue or chamber surrounding the 55 spherical Harrison elements H, and forming part of the flue system connecting the furnace with the stack M.

The water-tubes *c* and headers C of my improved boiler are, it will be observed, entirely 6c situated in the furnace-flues, as are also the spherical elements which form the steam and water receptacle of my boiler.

The deflecting-walls E and F cause the products of combustion from the furnace D to 65 cross the water-tubes *c c* three times, causing them also to come into close contact, and, indeed, to surround the headers C, especially those at the back of the boiler. The gases then escape through the opening K into the 70 flue L, where they pass over and among the spherical elements H, and finally escape into the stack M. By this arrangement I not only expose the inclined water-tubes or steam-generating part of my boiler to the greatest possible amount of heat, but by means of the great 75 surface of the spherical elements exposed in the flue L the steam in the upper portion of the receptacle H is dried and superheated, and thus one of the great defects of this class of 80 sectional boilers obviated.

The water-tubes *c* and headers C are, as is usual with this class of boilers, easily put together, and the headers being made in sections, this part of the structure is easily transported in packages of but small individual weight. In ordinary boilers of this class, however, the upper steam and water receptacle is large, cumbersome, and heavy, though I am aware that plans of making it in divisions 85 which can be more easily handled have been repeatedly suggested. My plan of making this part of the boiler of spherical elements makes it quite as easy to transport as are the lower portions, while at the same time it is 90 easily put together and has advantages, as before noted, over any of the constructions heretofore used.

As shown in the drawings, the products of combustion are permitted to enter the space 100 B' B² in front of the front headers, and I prefer to have them do so, as the whole of the

generating part of the boiler is thus exposed to the heat of the furnace; but the front headers may be closed up to form a fire-wall, if desired. The arrangement and number of the 5 deflecting-walls and bridges may also be varied, that shown being, I believe, well adapted for use.

It may be desired to bring the front of the receptacle H out to the front of the inclosing 10 structure, so that horizontal rows of the elements may be readily accessible; but I prefer to entirely inclose the whole boiler, making the front plates, R and S, of the enveloping 15 structure removable, so that the tubes and elements may be got at for examination, cleaning, and repairing.

I am aware that sectional boilers have been proposed and described in Hartley's patent of February 9, 1886, having an arrangement of 20 flues similar to that of my boiler. In such proposed construction, however, the arrangement of the steam and water space with respect to the tubular boiler below it differs entirely from mine, and the circulation of the 25 water and the conditions under which the steam separates from it are, in consequence, quite different. By the use of the intercommunicating spherical sections to form my superimposed steam and water receptacle, communicating with the headers at or near each 30 end, I not only obtain a boiler which, as a whole, is more easily transported than is usual, but I preserve the desirable features of a single cylindrical receptacle—to wit, the unob- 35 structed circulation of the water and separation of the steam therefrom—and in addition,

where the receptacle is situated in a flue, as shown, I secure a more efficient utilization of the heat of the furnace and obtain my steam more entirely free from water, or dry, than in any similar boilers in use.

Having now described my invention, what I claim as new, and desire to protect by Letters Patent, is—

1. The combination, with the tubes and 45 headers of a sectional boiler, of a superimposed water and steam receptacle composed of inter-communicating spherical elements, substantially as and for the purpose specified.

2. The combination, with the tubes and 50 headers of a sectional boiler, of a superim- posed water and steam receptacle composed of intercommunicating spherical elements and inclosed in a flue leading from the furnace to the stack.

3. The combination of the water-tubes c, 55 headers C, made in sections, and the water and steam receptacle H, made up of intercommunicating spherical elements, substantially as and for the purpose specified.

4. The combination of the tubes c, headers 60 C, and steam and water receptacle H, com- posed of intercommunicating spherical ele- ments, with the furnace D, deflecting-walls E, F, and G, opening K, flue L, and stack M, 65 all substantially as and for the purpose speci- fied.

HENRY WARDEN.
